ARCH SUPPORT

Joseph A. Amico, Rochester, N. Y.

Application January 3, 1948, Serial No. 438

3 Claims. (Cl. 36—71)

1

The human foot has five metatarsal bones which bones are long and narrow and are numbered from one to five, and the first metatarsal bone is in line with the big toe of the foot. Some or all of these metatarsal bones get out of place and get to an abnormal position in the foot and need special treatment to get them back to normal position. This most frequently occurs in connection with the second, third and fourth metatarsal bones and less frequently with the first metatarsal bone and still less frequently in the fifth metatarsal bone.

Shoes generally are made according to certain standards which is determined by the shape of the last on which the shoe is made. Feet that have the abnormal features must conform themselves to the standard shoes that are worn and this frequently causes discomfort in the abnormal foot wearing a standard shoe.

Heretofore arch supports have been made that contain more or less metal and which are used for the purpose of forcing the misplaced metatarsal bones back to position.

I have invented an insole and arch support that contains no metal. It consists of an ordinary leather insole to the under side of which is attached a well-known cookie, the shape of which is impressed on the insole. Under the cookie and the insole, I place the first metatarsal pad. The top of the insole is then covered with several coats of rubber cement. The shank portion of the insole is then covered with a perforated rubber pad, which is intended to come immediately under the arch of the foot.

This perforated rubber pad is soft enough so that it will compress to some extent under the pressure of the foot and will relax again with every step that the foot takes and this in turn causes an intermittent suction on the instep, that is it causes a suction with every step that the foot takes.

A second metatarsal pad is placed partly on top of the rubber pad and partly on the insole forward of the rubber pad. This assembly is then covered with a leather skin coating impregnated with ground clay which makes it absorbent as a blotter. This leather coating also protects the stocking.

For this purpose I start with an insole that is longer both at the toe and the heel than the shoe in which it is intended to be worn. It is necessary to bring the supporting pads to the correct position under the metatarsal bones of the foot, and for this purpose the insole must be cut away either at the toe or the heel or in both

places to bring the pads in correct position under the second, third and fourth metatarsal bones of the foot. Thereafter the insole can be inserted in the shoe and worn.

I have found that this insole and arch support will, in a large number of cases, bring the second, third and fourth metatarsal bones instantly and correctly back to the normal position or at least will start and gradually bring them back to correct position because it is more elastic than any metal support could be.

This insole, if necessary, can be worn for several weeks and can then be replaced with a second insole that will in another short period restore the metatarsal bones to the correct positions.

It will also be understood that while the first metatarsal bone needs correction less frequently, this arch support will bring the first metatarsal bone eventually back to position and will also bring the fifth metatarsal bone back to position, if out of position, which still much less frequently happens. This support, if necessary, can also be modified to better secure these results.

These and other objects of the invention will be illustrated in the drawings, described in the specification and pointed out in the claims at the end thereof.

In the drawings:

Figure 1 is a top plan view of the insole completely assembled for the right foot.

Figure 2 is a longitudinal section through the insole on the line 2x, 2x of Figure 1.

Figure 3 is a transverse section through the insole taken on the line 3x, 3x of Figures 1 and 2.

Figure 4 is a transverse section on the line 4x, 4x of Figures 1 and 2.

Figure 5 is a section through the heel pad, which pad is put under the insole and the location of it is indicated by the line 5x, 5x of Figure 1. This pad is about two and a half inches long and one-third of the width of the insole at the heel.

Figure 6 is a top plan view of the small size perforated rubber pad that I use to cover the upright part of the cookie and part of the insole.

In the drawings, like reference numerals indicate like parts.

In the drawings, reference numeral 1 indicates the insole that is preferably made of thin sole leather. This insole is normally longer than the shoe in which it is intended to fit and must be cut away at the toe or heel or at both places before it can be used in the shoe.

To the underside of the insole is attached a

cookie 4. The cookie is attached to the insole by a row of stitches indicated by the reference numeral 5. This row is indicated in dotted lines and the line outside of the line 5 and parallel thereto indicates the edge of the cookie. This cookie is separately pressed to shape and is stiff enough so that it will hold the insole to the concave convex form that is previously impressed on the cookie to which it is connected, so that the shape of the insole will correspond to the shape of the cookie and give the insole the fixed concave convex shape shown at 2 in Figure 2.

The concave portion under the insole is filled in with an elastic composition which composition is made up of a large percentage of cork and a very small percentage of rubber held together with a binder. This forms a supporting pad 3, known as the first metatarsal pad.

Under the insole and in the concave formed by the cookie is sometimes placed an extension 3a of the pad 3 which is intended to support the first tarsal bone. This extension is also made of a composition of a large percentage of cork and a small percentage of rubber.

Under the insole and in the middle of the insole and somewhat in advance of the first supporting pad is placed a second supporting pad 6 composed of a smaller percentage of cork and a considerably larger percentage of rubber held together with a binder than is contained in the first pad 3 above named. This pad is more elastic or softer and more compressible than the first pad and forms an extension in the pad 3.

This pad is known as the second metatarsal pad. The first pad 3 under the insole is intended to support, more especially, the nerves and ligaments of the foot and the second pad 6 is intended to support the three metatarsal bones of the foot; namely, the second, third and fourth metatarsal bones. The pad 3 has a so-called 50 percent of elasticity and the metatarsal pad 6 has a so-called 75 percent of elasticity under the pressure of the foot. That is, under the pressure of the foot the pad 3 may compress 50 percent and the pad 6 may compress 75 percent or thereabouts.

At the rear of the metatarsal pad 6 and partially underlying it, a rubber pad 8 is placed on top of the insole, which pad covers the upright part of the cookie 4 as well. That is, the part above the insole shown at the top of Figure 1. This rubber pad is perforated with a large number of small holes, or in other words is made porous by these holes.

This rubber pad is intended to warm or heat up the sole of the foot and make it perspire and the holes in the rubber pad permit the moisture to pass through and be absorbed by the cookie, the insole and the pads above referred to. To increase the heating and perspiring effect of the rubber pad, a larger pad may be used which larger pad extends across the mid portion of the insole enclosed between the two dotted lines marked 8a-8a, or any size of rubber pad between these two pads may be used more or less.

The insole with its cookie and pads so made up is then measured to fit the foot and the shoe in which it is to be worn so that the pads 3 and 6 will come under the second, third and fourth metatarsal bones as they occur in the individual foot. To secure this result the insole is made front and back longer than the insole should be to fit the shoe and in order to bring the pads to the correct position under the sole, the insole is cut away at the toe and the heel so as to posi-

tion the pads correctly under the metatarsal bones of the foot. If more is cut away at the toe, then less will be cut away at the heel or vice versa so that the total amount cut away will be substantially the same in each case for insoles of the same size.

Preferably before the toe and heel of the insole are cut away several coats of rubber cement are placed on top of the insole and on the pad 6. These coats of rubber cement will close up the pores of the insole and on top of this is placed the skin 9, the edges of which are turned under the insole. This skin is made preferably of thin sole leather. It has no oil in it. It is dry and is impregnated with pulverized clay so that it can freely absorb as a blotter absorbs.

In this way, a large number of complete insoles for a particular size of shoe can be made up and after the measurements of the foot have been taken with reference to the position of the second, third and fourth metatarsal bones and with reference to the toe and the heel of the foot, the insole can be cut away at the toe and the heel so that when the insole is placed in the shoe, the metatarsal pads of the insole will be under and will correctly support the metatarsal bones so as to bring them back to normal position, which insole can be replaced in a few weeks by a second insole that will in another short period restore them fully to their correct position.

In a large number of insoles fitted to shoes of the same size the position of the metatarsal pads will occur at different distances from the heel and toe of the insole so it is possible that no two of them will be alike, but each insole will properly support the metatarsal bones of the foot to which it is adapted.

The skin 9 will prevent the stocking on the foot from sticking to the rubber cement on the insole. The rubber pad 8 is perforated with holes. These holes are spaced apart by a distance about equal to the diameter of the holes. These holes are closed on the bottom by the insole, so that the holes form cups and even though this rubber pad is covered by the skin coating these holes have a suction effect on the sole of the foot with every step taken. It is also true that the skin is so thin that it is like a tissue. It is split from sole leather and is known to the trade as "split leather" and is split from the flesh side of sole leather and is therefore porous so that it can be impregnated with clay.

The concave convex areas of the insole will fit the arch of the foot close enough so as to bring the holes close up to the skin on the bottom of the foot and the perforations will have a suction effect which massages the underside of the foot and stimulates circulation and causes the sole of the foot to perspire freely and this causes the foot to throw off impurities. The perspiration of the foot is acid and the acid of the perspiration and the impurities that are brought out with it are absorbed by the leather skin and they work their way through the coats of rubber cement and the perspiration and impurities are absorbed by the insole so much so that after a few weeks of wear the skin will become cracked and the insole will become dark and stained in color and will become brittle and the weight of it will become increased and for sanitary reasons the insole will have to be replaced with another insole.

I have also found that the second insole that

replaces the first one will last for a much longer time than does the first one.

The insole is sometimes supplemented by the use of a heel pad 10 shown in Figure 5, which pad is built up on the bottom of the insole with the same composition of cork and rubber that is used under the insole in the arch.

I have formed the first and second pads of cork and rubber with a binder by mixing the composition in a pasty form and applying them to the bottom of the insole and to the top of the insole and then let them set and dry, but I have found it easier to use the same composition preformed in dry sheets and from which I have cut the two pads to size before they are fastened to the insole and the pads are trimmed either before or after they are fastened to the insole.

The first pad is left with its full thickness on the edge exposed under the cookie as is shown in Figure 3 but it tapers off thin on the other three edges. The second pad also is thick in the center as shown in Figure 4 and tapers off around the edges that the edges gradually merge with the surface of the insole, to which they are attached, thus avoiding unnecessary ridges under the foot.

It will also be understood that while the insole shown in the drawing is for the right foot, corresponding insoles have been and can be made for the left foot, the parts being reversed symmetrically from right to left as they would appear in the drawing when held up to the light and looked through from the back.

It will also be understood that in addition to the stitches, the cookie can be cemented to the insole and both the first and second pads and the rubber pad and the skin covering are all held in place by rubber cement. This is necessary in order to give the insole and various parts of it the flexibility and elasticity that is desired.

I claim:

1. An arch support comprising an insole having a narrow intermediate part, a cookie having a convex pattern on its top side, said cookie being fastened on the underside of the insole at one side thereof at its narrow part so that the insole conforms in shape to a portion of the top of the cookie, said cookie having a concave pattern on its underside, an imperforate pad having low elasticity placed in the concave part under the cookie and beneath the insole, said cookie and said first named pad holding that intermediate part of the insole in the form of an arch, an imperforate second pad placed on top of the insole above the cookie and partially in advance of the said first named pad, said second pad having a greater degree of elasticity than the first pad, one or more coats of rubber cement placed on top of the assembly, a dry absorbent skin coat of

ground clay-impregnated leather placed on top of the rubber cement.

2. An arch support comprising an insole having a narrow intermediate part, a cookie having a convex pattern on its top side, said cookie being fastened on the underside of the insole at one side thereof at its narrow part so that the insole conforms in shape to a portion of the top of the cookie, said cookie having a concave pattern on its underside, an imperforate pad having low elasticity placed on the concave part under the cookie and beneath the insole, said cookie and said first named pad holding that intermediate part of the insole in the form of an arch, a second imperforate pad placed on top of the insole above the cookie and partially in advance of the said first named pad, said second pad having a greater degree of elasticity than the first pad, one or more coats of rubber cement placed on top of the assembly, a dry absorbent skin coat of ground clay-impregnated thin sole leather placed on top of the rubber cement, a perforated sheet rubber pad placed beneath the skin coat on top of the arch of the insole.

25 3. An arch support comprising an insole having a narrow intermediate part or shank, a cookie having a convex pattern on its top side, said cookie being fastened on the underside of the insole at one side thereof at its narrow part so that the insole conforms in shape to a portion of the top of the cookie, said cookie having a concave pattern on its underside, an imperforate pad having low elasticity placed in the concave part under the cookie and beneath the insole, said cookie and said first named pad holding that intermediate part of the insole in the form of an arch, a second imperforate pad placed on top of the insole above the cookie and partially in advance of the said first named pad, said second pad having a greater degree of elasticity than the first pad, a rubber pad placed on top of the shank of the insole, said rubber pad being full of perforations which perforations are spaced apart by a distance about equal to the diameter of the 35 perforations and a dry absorbent skin of ground clay-impregnated thin sole leather overlying said insole, second pad and rubber pad, and secured thereto by rubber cement.
